UNITED STATES PATENT OFFICE.

JAMES H. RAND, JR., OF NORTH TONAWANDA, NEW YORK.

CARD-INDEX.

1,268,489.

Specification of Letters Patent. Patented June 4, 1918.

Application filed October 4, 1915. Serial No. 53,885.

To all whom it may concern:

Be it known that I, JAMES H. RAND, Jr., a citizen of the United States, and resident of North Tonawanda, in the county of 5 Niagara and State of New York, have invented new and useful Improvements in Card-Indexes, of which the following is a specification.

This invention relates to a card index system of the kind described in an application 10 filed by me jointly with James H. Rand April 8, 1914, Serial No. 830,508, wherein there is described a card system of the overlapping card type, in which a series of card-holders or card supports are removably 15 mounted in a frame, and a series of cards are removably held by the card-holders in such manner that they may be removed from their respective card-holders and supports 20 without removing the latter from the frame, thus reserving the space belonging to any card when it is removed, and visually indicating its absence from the series.

The present invention consists in a novel 25 form of card index structure embodying such general idea, as hereinbefore more fully described and particularly pointed out in the claims.

In the accompanying drawings in which 30 one embodiment of the invention is shown,—

Figure 1 is a face view, partly broken away, of a card-support and card containing the invention;

Fig. 2 is a face view of the card-support 35 and spacer alone;

Fig. 3 is a plan view of the card-support and hinge member shown in Fig. 1;

Fig. 4 is an enlarged detail, showing one end of said support in perspective;

Fig. 5 is a section on line 5—5 of Fig. 1; 40 and

Fig. 6 is a face view, partly in section, of a fragment of the assembled card index system.

Throughout the specification and claims 45 the word "card" is used to denote any sheet of any suitable material.

The several card-supports are mounted in a suitable frame A (Fig. 6) of usual construction, having inturned guide flanges α to form opposed channels which engage and retain the ends of the card-supports.

Each card-support, as herein shown, consists of a strip or bar of resilient metal, B, bent up at its ends to form heads b which fit under the guide flanges α of the frame.

Said supports are adjustable and interchangeable in the frame and may be removed therefrom by springing their central portions outward and thus withdrawing 60 their ends from the channels of the frame. The inner face or shoulder b' of each head, which projects forward from the body of the strip B, is provided with a socket or hole b^2 preferably extending a short distance into the body of the strip B as best shown in Figs. 2 and 4.

Each card C is removably supported by and hinged to its card-support B by means of a resilient rod c , extending through a 70 fold or loop c^2 of the card, or otherwise secured to its edge, and projecting beyond the lateral edges of the card to form a pair of trunnions or hinge members to engage the sockets b^2 , which constitute a complementary pair of hinge members on the card-support B. Said trunnions instead of being the ends of a single rod c might be in the form of two separate rods or pins secured at either side of the card, or the hinge members 75 might be merely reversed, and the rods or pins be secured to the heads b of the bar to project inwardly into the end of loop c^2 formed by the fold of the card.

Said hinge members may be disconnected 80 and the card removed from its support without removing the latter, by bending or springing the card and rod c forward away from the frame, whereupon the rods will be withdrawn from their sockets.

Said cards are thus hinged so that they 85 may be swung upward on their hinges as indicated by the upper card C in Fig. 6, for the purpose of inspecting or writing on the cards, and any card may be easily and 95 quickly removed from the series by disconnecting the hinge members as above explained without removing the support B from the frame.

A further important feature of the invention 100 is a signal normally concealed by each card in the series, which is uncovered when the overlying card is removed from the series and constitutes a conspicuous visual indication that a card is missing from the 105 space where the signal appears. Such signals are placed directly on the removable cards themselves, and may consist of a sign, symbol, or any suitable mark, preferably in a conspicuous or contrasting color. The 110 signal is shown in Fig. 6, by way of illustration, as a colored area S, contrasting with

the color of the card, and bearing if desired 5 the words "Card out." The signal S on each card is normally concealed behind the exposed marginal portion of the next adjacent overlying card, but when any card is removed, its absence will be visually indicated by the exposure of the underlying signal. Thus in Fig. 6 it will be noted that the card is missing from the card-supporting member B immediately below the top card C. When the top card C is swung down its lower edge will occupy the position shown at dotted line 2, thus leaving exposed the signal S on the next card underneath, showing that card belonging in the intervening space is out. Similarly the absence of a card is shown at the bottom of Fig. 6.

I claim:

20 1. In a card index system, a frame having guides, a series of card-supporting and spacing members, each removably mounted in the frame and having laterally enlarged parts located in said guides whereby said members are prevented from movement past each other in the guides, and a series of cards having hinge connections with said members, said cards being removable from their respective supporting and spacing 30 members without removing the latter from the frame.

2. In a card index system, a frame having guides, a series of card-supporting and spacing members, each comprising a bar of resilient material removably mounted in the frame and having laterally enlarged end parts located in said guides whereby said members are prevented from movement past each other in the guides, and a series 40 of cards having hinge connections with said members, said cards being removable from their respective supporting and spacing bars without removing the latter from the frame.

3. The combination of a frame having guides, a series of card-supporting and spacing members, each comprising a thin bar removably mounted in the frame and having laterally bent ends forming enlarged end parts located in said guides, and a series 50 of cards having hinge connections with said parts, said cards being removable from their respective supporting and spacing bars without removing the latter from the frame.

55 4. In a card index system, a frame, a series of card-supporting and spacing members, each comprising a bar having a hinge socket at each end, and a series of cards

each having a pair of trunnions projecting beyond its sides detachably engaging said 60 sockets, said cards being removable from their respective supporting and spacing bars.

5. In a card index system, a frame, a series of card-supporting and spacing members, each comprising a bar having a hinge socket at each end, and a series of cards each having a rod secured to its upper edge and forming a pair of trunnions projecting beyond its sides detachably engaging said 70 sockets, said cards being removable from their respective supporting and spacing bars.

6. In a card system, a frame having inwardly facing guide channels, a series of 75 card-supporting and spacing members, each comprising a bar having forwardly projecting heads at its ends engaging said guide channels, each head having a hinge member, and a series of cards each having a pair 80 of complementary hinge members removably engaging the hinge members of the bar.

7. In a card system, a card-supporting and spacing member comprising a bar, and a forwardly projecting head at each end of 85 the bar, said heads having hinge members.

8. In a card system, a card-supporting and spacing member comprising a bar of resilient material, and a forwardly projecting head at each end of the bar, said heads 90 having hinge members.

9. In a card system, a card-supporting and spacing bar having each end bent to form a head and an inwardly facing shoulder, and each shoulder having a hinge socket 95 therein.

10. A card system, comprising a series of card-supporting and spacing members, and a series of cards held by said card-supporting and spacing members, and removable therefrom, said card-supporting and spacing members being adapted to support the cards one in front of another with their edges exposed, and a signal on each removable card normally concealed behind the exposed portion of the next adjacent overlying card, whereby the absence of any card from its place will be visually indicated by the exposure of the underlying signal.

Signed by me at North Tonawanda, this 110 20th day of September 1915.

JAMES H. RAND, Jr.
